UNITED STATES PATENT OFFICE

PERRY B. DILLMAN, OF GREAT FALLS, MONTANA

PORTABLE BRIDGE

Application filed March 14, 1930. Serial No. 435,933.

The object of this, my present invention, is the provision of a portable swingable bridge designed for spanning ditches, ravines, docks and girders in industrial plants, etc., and my object is the provision of a bridge for this purpose that is pivotally supported at one of its ends and has its said end counter-weighted so that a slight pressure upon the said end of the bridge will cause the same to assume an upright position to permit objects passing between the space to be spanned by the bridge and also swingable to span such space when a pressure in an opposite direction is exerted thereagainst, there being means for holding the bridge in such bridging position.

A still further object is the provision of a hand operated bridge of this character which has its weighted end provided with a box for a ballast that affords the counter-balancing means.

A further object is the provision of a bridge for this purpose which shall be light in construction and readily moved from place to place when desired.

To the attainment of the foregoing and other objects which will present themselves the improvement also resides in certain other novel features of construction, combination and operative association of parts, satisfactory embodiments of which are disclosed by the accompanying drawings.

In the drawings:

Figure 1 is a plan view of a bridge construction in accordance with this invention, showing the same in spanning or operative position.

Figure 2 is a substantially longitudinal central sectional view therethrough.

Figure 3 is a perspective view of the ballast receiving box with the cover thereof removed.

Figure 4 is an elevation with the bridge in upright or vertical position and the supporting standards therefor mounted on rollers.

Figure 5 is a view looking at right angles to the showing of Figure 4.

Figure 6 is a transverse sectional view on the line 6—6 of Figure 1.

Figure 7 is an inverted perspective view looking toward the balancing end of the bridge.

Figure 8 is a similar view looking toward one of the side plates of the trough.

When the improvement is designed to span ravines, gullies and the like the standards of the improvement are embedded in one bank of the gully, but when the device is employed for spanning canals, docks in industrial plants and girders in steel structures the standards are journaled on rollers and are arranged for movement in trenches as will hereinafter be fully described.

Referring to the drawings in detail and to Figures 1 to 3 in particular, the numerals 1 designate the supporting standards. As disclosed by Figures 1 and 2 of the drawings these spaced standards have their lower ends pointed and are embedded in one of the banks of a ditch, ravine or the like. The standards 1 project a suitable distance above the top of the bank 2 and the same are held spaced by short shafts or trunnions 3 that are journaled therein and which are formed on the ends of an axle 4. The trough-like portion of the ballast box rests upon the upper face of the axle. The box proper is arranged above the trough 5 and is indicated for distinction by the numeral 6. The bottom of the box is provided with an opening 7 that communicates with the trough and by reference to the drawings it will be noted that the trough projects a suitable distance beyond the forward end of the box 6 and has its upper edges beveled or inclined downwardly, the widened portion of the said edges being disposed in a line with the top of the box.

The trough 5 is constructed of thin boards, and nailed or otherwise secured on the outer faces of the side members of the trough are triangular plates 8 whose upper edges are disposed in the same plane as the angle edges of the projecting corners of the trough and whose ends are disposed in a line with the ends of the said projections and whose lower edges are arranged in a line with the top of the trough proper. These reinforcing plates 8 are designed to have their lower edges disposed over and nailed or otherwise secured.

to the upper edges of the longitudinally extending beams 9 of the improvement. The beams 9 are of stock size, and are of the same length. The beams are likewise preferably secured to the sides of the trough and the ends of the beams terminate a suitable distance inward of the inner ends of the trough. The beams rest against the bottom of the box 6 and are nailed or otherwise secured thereto. 10 The axle 4 is square or rectangular in cross section and passes through and contacts with the walls of openings in the beams. On the outer faces of each of the beams 9 there are fixed spacer blocks 10, the same being preferably in the nature of 4" x 4" timbers and on the outer face of these spacer members 10, and flush with the outer sides of the box 6 there are arranged plates 11 which are in the nature of comparatively short timbers and 20 of a width corresponding to that of the beams 9. The axle 4 passes through and contacts with openings in the center of the plates 11 as well as openings in the beams 9. Bolt 12 passes through the plates 11, the spacer blocks 10, the beams 9 and the walls of the trough 5 holding these parts rigidly associated. Another long bolt 13 passes through the plates 11, spacer blocks 10 and beams 9 to 25 add to the rigidity of the structure, and to effectively connect the parts constituting the same. The bolts preferably have their heads embedded in one of the plates 11 and the nuts which engage the bolts are embedded or pocketed in the second plate 11. 30 This construction, it will be noted, strengthens and reinforces the balancing end of the bridge. The open top of the box 6 is covered by transversely arranged boards 14, the end 40 boards being permanently fixed to the box but the central board being removable so that a ballast 15 may be inserted in the box and thereafter the central board is nailed to the box. Arranged over the angle corners of the trough and the triangular reinforcing plates 45 8 on such corners there are other boards 16, certain of such boards being fixedly nailed to the plates and to the angle corners of the trough, but one of said boards being removable for the insertion of ballast to be inserted into the trough 5, and when the ballast is received therein the loose board is fastened. Obviously a quantity of the ballast will fall 50 into the trough through the opening 7 in the bottom of the box 6. The beams 9 extend a desired distance beyond the balancing end of the bridge, and the said beams are held in spaced parallel relation by bolts or analogous means 17 and 18, 60 respectively, although the upper and lower spacer members or bolts are arranged in a line with each other. The upper edges of the beams are covered by transversely arranged planks or boards 19 which are nailed thereto

and which provide the platform for the bridge.

The outer corners of the beams 9 are rounded and these corners as well as the lower edges of the beams are shod by metal plates 70 20.

The upper and outer combined brace and spreader element 18 may be engaged by a hook 21 on the end of a rope or cable 22, and in the present showing I have inserted in the 75 bank 23 against which the bridge is swung, when bridging the space between the banks 2 and 23, a stake 24 that has pivotally secured to its upper end a hook 25 to engage with the lower and outer combined brace and spreading element 17. However, neither the stake 24 nor the hook 25 are an absolute requirement in my invention.

The weighted or counter balancing and pivoted end of the bridge will normally swing the same to an upright and vertical position and the bank 2 is excavated for the reception of the box and trough when the bridge is in such vertical position. Manual pressure against the upright bridge will cause the same to swing upon the trunnions 3 to horizontal position or against the top of the bank 23. The operator placing his weight upon the bridge will hold the same in such horizontal position so that he can walk over the bridge and, should he find it desirable to sustain the said bridge in such horizontal or bridging position he, with his weight still on the outer end of the bridge, 103 can apply the hook 21 to the outer element 18 and fasten the rope or cable to a suitable support or when the stake 24 is employed he can swing the hook 25 over the outer and lower element 17. It is to be understood, however, that these holding means are only 108 employed when the bridge is to span the gap for any determined length of time and a removal of the holding means will permit the counter balancing or weighted end of the bridge to again swing the same to its initial 113 vertical position. When the rope is removed it is coiled and placed out of the way when the bridge is in use and when the bridge is in upright position the rope may hang from the bridge over the bank 23 where it is secured to a high stake in such manner that small children will not attempt to unfasten it and pull the bridge down. In operation care is exercised so that the bridge is gradually lowered 118 to prevent the same crashing into the bank 23, while care is also exercised to prevent the bridge ascending too abruptly and this is attained by the gradual release and slackening of the cable 22.

In Figures 4 and 5 the bridge construction is similar to that previously described but the standards 20' are provided with additional spacer elements 26. The lower and straight end of each of the standards 20' is received 123 in a socket 27 provided in a plate 28, the said

plate having its sides provided with depending portions 29 that are in the nature of angularly disposed ears and these ears have openings for the pivot or trunnion of rollers 5 30. The rollers are arranged upon the floor of a trench 31 with which one bank of a canal is provided or which may be built in a dock at an industrial plant or along one side of a girder in permanent steel structures, 10 when travel is to be made from one bank of a canal to another or from one girder to another girder.

In addition to the above mentioned commercial purposes the improvement may be 15 constructed upon a small scale and used as a toy for affording amusement to children.

The device and the advantages thereof will, it is thought, be understood and appreciated by those skilled in the art to which 20 such invention relates, without further detailed description, it being thought merely necessary to add that I do not wish to be restricted to the precise details herein set forth and, therefore, hold myself entitled to 25 make such changes therefrom as fairly fall within the scope of what I claim.

Having described the invention, I claim:

1. A bridge for spanning spaces, including spaced supporting standards, beams, an 20 axle having trunnions journaled on the beams, a weight receiving box supported on the axle between the beams, a removable closure for the box, a platform arranged on the beams and the weight in said box designed to 25 counter balance the beams to swing the bridge to normally upright position.

2. A bridge for the purpose set forth, including spaced supporting standards, rollers journaled on the lower ends of the standards, 0 a box having a lower trough extending therefrom and disposed between the standards, beams fixed to the sides of the trough for underlying the box and received between the standards, a shaft fixed to the under face of the trough and having trunnions that are journaled in the standards, spacer means between the standards, one of which underlying and being secured to the trough, said box having an opening communicating with the trough, removable covers for the trough and upper ballast box and a platform fixed on the beams.

3. A bridge swingable from one to another bank of a ravine, gully or the like, including a pair of spaced standards set in one bank, a trough having its sides, adjacent to its outer end formed with extensions whose outer ends are inclined downwardly, a triangular plate fixed on the said corners of the trough, a box disposed over the trough, fixed thereto and extending laterally therefrom and contacting with the inner ends of the projections and triangular plates on the trough, a pair of spaced longitudinally extending beams having their outer ends rounded and their

lower edges and said ends shod with metal and also having their inner ends disposed to contact with the sides of the trough to underlie the box and the triangular plates are to be fixed to these elements, a cross sectionally square axle disposed below and in contact with the trough and let through openings in the boards, spacer blocks fixed on the outer sides of the boards, plates underlying the box, having their outer faces flush with the 75 sides thereof, fixed to the spacer blocks and having openings through which the axle is received and the ends of the axle having trunnions thereon which are journaled in the standards, top boards for covering the box 80 and the projecting end of the trough, one of each of said boards being removable, boards comprising a platform fixed on the beams, staggeredly related brace and spreader members for the beams, the outer members being disposed in a line with each other, said 85 box having an opening therethrough to communicate with the trough and the box and trough designed to receive a ballast therein to provide a counter balancing weight for 90 swinging the bridge to a vertical position and the beams being of a length to span both of the banks.

In testimony whereof I affix my signature.
